APPARATUS FOR CONTROLLING THE FLOW OF REFRIGERANT IN REFRIGERATING APPARATUS

Application filed July 9, 1926. Serial No. 121,301.

This invention relates to a method of and apparatus for controlling the flow of refrigerant in refrigerating apparatus. It has to do particularly with the feeding and the control of the flow of the refrigerant into the cooling device of a mechanical refrigerating system.

It is an object of the present invention to provide means positioned between the condensing or liquefying apparatus and the cooling unit for restricting and accurately controlling the feeding of the refrigerant to such unit will be of a predetermined rate corresponding to the capacity of the refrigerating apparatus. This novel device not only restricts and controls the flow of refrigerant but so restricts the flow in such a novel manner that only a simple, compact device is necessary which entirely does away with ordinary expansion valves and float valves such as have been used in the past.

A further object of this invention contemplates the provision of a device which not only predetermines the flow of the liquid in accordance with the capacity of the unit, but which also positively feeds the refrigerant to the cooling device in such a manner as to prevent any back flow of the refrigerant either in a liquefied or a gaseous condition. A further object of the invention relates to the manner of restricting and feeding the refrigerant in order to obtain a high pressure of such refrigerant and obtaining a uniform flow of the refrigerant without the necessity of using a very small orifice of short length or, in other words, obtaining uniform predetermined restricted flow with a minimum possibility of clogging or stopping of the refrigerant.

Fig. 1 is a fragmentary front elevation partly diagrammatic illustrating the nature of, and manner of embodying, my novel device in combination with an automatic refrigerating system.

Fig. 2 is an enlarged detail view partly in section, of my novel capillary tube for restricting and controlling the flow of refrigerant and also showing one manner of connecting the same to the inlet of a cooling unit.

Heretofore, in the refrigerating art, in

regulating and controlling the flow of refrigerant to the cooling device, it has been customary to use some form of an expansion valve or some form of a float valve for maintaining the flow or level of the refrigerant to and in the cooling unit. These various types of valves have been more or less efficient when operating ideally, but on the other hand, these various valves by reason of their complicated structure have been the source of a large amount of service trouble in commercial domestic mechanical refrigerating units.

The present device obviates all types of valve structures for controlling the transmission of the refrigerant to the cooling unit. It is positive in its action and is extremely compact and simple. Attempts have been made in the past to control the flow of refrigerant to the cooling unit and to do away with the use of float valves and expansion valves by flowing the refrigerant through a very small orifice and thus restricting the flow of refrigerant to a predetermined degree. This form of restriction has not proven successful for many reasons, one of which is a tendency of such an orifice to easily clog up and thus make it necessary to stop the entire system until the orifice can be removed and cleaned. The present invention relates in a measure to the idea of restricting the flow of the refrigerant to control its transmission to the cooling chamber, but instead of merely providing the plain restricting orifice, I have discovered that by inserting a capillary tube between the condenser supply tube and the cooling unit, that the capillary action of the refrigerant passing through this tube will create the required amount of back pressure and resistance to predetermine the rate of flow.

More specifically, my invention relates to the provision of a capillary tube which, in its preferred form, is coiled so as to present a helical or spiral passageway for the refrigerant. Such a capillary tube is illustrated in Fig. 2 and may be designated 1. It is preferably positioned adjacent to the cooling unit and may be connected to the cooling unit intake by means of a suitable union 2 such as

illustrated in Fig. 2. The intakes 3 for connecting the capillary tube to the cooling unit, are preferably somewhat larger in diameter than the diameter of the capillary tube 5 whereby the refrigerant is caused to expand as it enters the cooling unit. In the drawing, I have diagrammatically illustrated a refrigerating system wherein 4 designates a suitable compressor for withdrawing the evaporated or expanded refrigerant gases from a cooling unit 5. A condenser 6 is adapted to receive the compressed refrigerant from the compressor, and to either liquefy or maintain the liquefaction of the compressed refrigerant. The condensed refrigerant in flowing under pressure from the condenser to the cooling unit passes through the capillary tube 1 and thus its entrance into the cooling unit is restricted and controlled in a predetermined manner in accordance with the diameter and length of the coiled capillary tube.

By embodying capillary action in restricting and feeding the refrigerant to the cooling unit, it is possible to use a relatively large diameter capillary tube corresponding to the extremely small orifice as has heretofore been necessary in using a plain restricting orifice. The length of the capillary action and the capillary tube compensates for and makes up for the relatively large diameter of the tube. In other words, the capillary tube permits of a reasonably larger hole and its resistance is created by its length.

I have found that in a refrigerating unit 25 having a compressor operating under average pressures and a cooling unit of average capacity, a coiled capillary tube, approximately 36 inches long and .037 inches in diameter, satisfactorily controls the flow of refrigerant and maintains the level of refrigerant in the cooling unit.

The coiled capillary tube, by reason of the coils, adds additional resistance to the flow of the refrigerant, and by the capillary action 45 prevents any back flow of the refrigerant. Each helical coil acts as a little hydraulic trap and thus affects the positive feeding of the refrigerant towards the cooling unit. It will be understood that this capillary coil 50 may be varied in length in accordance with the capacity of the particular unit in which it is embodied, and in conformity with the predetermined rate of flow of refrigerant desired. With a certain head pressure or a 55 certain back pressure and with a predetermined R. P. M. of the compressor, it will be possible to accurately regulate and predetermine the rate of flow of refrigerant to the cooling unit by utilizing the capillary coil of 60 a length in accordance with such predetermined head pressure and R. P. M. of the compressor.

It will thus be obvious that I have provided an extremely simple, positive acting and effi-

cient device for regulating and accurately controlling admission of refrigerant to the cooling unit of a refrigerating system whereby the level of the refrigerant is in such unit may be maintained approximately constant due to this predetermined restriction of the refrigerant by the capillary tube.

It will be understood that where I have referred to the particular application of my invention to mechanical refrigerating systems, that the word "mechanical" has reference to the use of refrigerating systems having a compression system operated by means of a pulsating piston type compressor.

What I claim is:

1. In a mechanical refrigerating system of the mechanical compression expansion flooded type the combination of a pulsating piston type compressor, a condenser, a cooling unit, and a single helical coil capillary tube positioned between the condenser and cooling unit and proportioned as to length and diameter relative to the capacity of said compressor, condenser and cooling unit as to restrict the flow of refrigerant and maintain the transmission to the cooling unit at a predetermined rate, said capillary tube connecting with the cooling unit and condenser.

2. In a refrigerating machine of the mechanical compression, flooded type, the combination of a compressor, a condenser and an evaporator, pipe connections between the evaporator, compressor and condenser, in the order named and a single capillary tube between the condenser and the evaporator of such length and diameter as will maintain a predetermined ratio between the pressures in the condenser and evaporator during the operation of the compressor whereby a mass of liquid is maintained within substantially predetermined limits at all times in said evaporator during normal operation.

3. In a refrigerating machine of the mechanical compressor flooded type, the combination of a compressor, a condenser and an evaporator, pipe connections between the evaporator, condenser and compressor in the order named, and a single capillary tube, said tube being located between the condenser and the evaporator and of such length and diameter as will maintain a predetermined ratio between the pressures in the condenser and evaporator during the operation of the compressor and minimize any tendency of the tube to clog, the said parts of the refrigerating machine and the refrigerant charge being so co-ordinated that the single capillary tube is adapted to function as the regulating device of the flow between the condenser and the evaporator and by reason of the said co-ordination the liquid level in the evaporator is maintained between narrow limits.

THOMAS E. CARPENTER.
